UNITED STATES PATENT OFFICE

BO KARL GEORGE EHNBOM, OF STOCKHOLM, SWEDEN, ASSIGNOR TO ELECTROLUX
SERVEL CORPORATION, OF NEW YORK, N. Y., A CORPORATION OF DELAWARE

REFRIGERATION

Application filed October 15, 1928, Serial No. 312,624, and in Germany January 6, 1928. Renewed
September 29, 1930.

My invention relates to refrigerating apparatus and particularly to types of apparatus including parts wherein there is gas and liquid contact over extended surfaces. 5 In one phase of my invention it relates to refrigerating apparatus of the absorption type and particularly to refrigerating apparatus wherein a cooling agent diffuses into an auxiliary agent and is subsequently separated 10 from the auxiliary agent by absorption into a liquid.

The purpose of my invention is to improve refrigerating apparatus so as to increase the effectiveness of certain functions for a given size of parts. I aim to provide a large 15 surface for gas and liquid contact within a small volume occupied by the parts of the apparatus in which the gas and liquid contact takes place while at the same time providing effective heat transfer.

In applying the invention to refrigerating apparatus wherein series of plates are used on which liquid is held, I provide means on the under-sides of such plates for retaining a 25 film, preferably a capillary film, of liquid adjacent the plates. The means for providing the capillary film on the under-sides of the plates is preferably metallic in order to provide good heat transfer between the inside 30 and outside of the vessel in which the plates are placed. While various means of accomplishing the result are possible I prefer to employ metallic wire screening held underneath such plates and adjacent thereto and so arranged as to contact liquid placed on the upper-sides of the plates so that the liquid may be driven by capillary attraction to the under-sides of the plates.

The invention will be described more in 40 detail with reference to the accompanying drawings showing several forms of apparatus embodying the invention and applied to a particular type of refrigerating apparatus or system. It will be understood, however, 45 that the invention is not limited to the particular type of apparatus described.

On the accompanying drawings:

Fig. 1 shows an absorption refrigerating system to which the present invention is applicable;

Fig. 2 shows one type of plate which may be used in the absorber or evaporator of Fig. 1, this type being diagrammatically indicated in Fig. 1;

Fig. 3 is a top view of the plate shown in Fig. 2;

Figs. 4 and 5 show a cross-sectional and a bottom view respectively of a modified type of plate:

Fig. 6 is a cross-sectional view of a third type of plate taken on the lines 6—6 of Fig. 7;

Fig. 7 is a bottom view of the view shown in Fig. 6; and

Fig. 8 shows still another form of plate.

The system of apparatus shown in Fig. 1 comprises a generator 10 which is divided by a partition 13 into two parts, a main generator 11 and an auxiliary generator 12. A flue 14 extends centrally through both auxiliary generator 12 and the main generator 11.

A suitable source of heat, as for example the gas burner 15, is located below, and may extend upwardly within, flue 14. A thermosiphon or percolator conduit 16 establishes communication between auxiliary generator 12 and main generator 11. The lower end of conduit 16 extends for some distance within auxiliary generator 12. The portion of conduit 16 within auxiliary generator 12 is provided with one or more capillary ports 17.

A conduit 18 communicates with the upper part of main generator 11 and extends, inclined to the horizontal, upwardly to rectifier 20. Rectifier 20 comprises a U-shaped member 21 around one branch of which is a member 22 to which conduit 18 is connected. Connected to the upper part of member 22 is a condenser tube 23 which passes in heat exchange relation with a cooling water conduit 24 and is connected to the right-hand branch of U-shaped member 21, as shown. The branch of the U-shaped member 21 which is within jacket member 22 is open at the top so that it communicates with condenser tube 23. This branch is surrounded by baffles 25 within member 22.

A conduit 26 is connected to the lower part of the rectifier, extends downwardly within conduit 27, horizontally through heat exchanger 28, upwardly through conduit 29

and terminates in a bend 30 which extends into an evaporator 31 situated within the space to be cooled. A conduit 32 connects the lower part of evaporator 31 with heat exchanger 28. The heat exchanger comprises a head 33 and a head 34 forming end chambers 35 and 36. These end chambers are connected by tubes 37. A space 38 is formed between heads 33 and 34 and outside tubes 26 and 37. To this space 38 conduit 32 is connected. A conduit 39 connects the lower part of space 38 with the lower part of an absorber 40. Conduit 27 connects the upper part of absorber 40 with chamber 35.

15 A conduit 42 connects the lower part of absorber 40 with the upper part of auxiliary generator 12. A conduit 43 connects the lower part of main generator 11 with the upper part of absorber 40. These conduits are in heat exchange relation as indicated at 44.

20 Heads 33 and 34 are provided with apertures to permit entrained liquid in spaces 35 and 36 to drain into space 38 and thence to the absorber. A vent pipe 47 connects the rectifier with space 38. The absorber is cooled by a cooling water coil 48 which is connected with conduit 24.

25 Evaporator 31 and absorber 40 contain plates 50 the nature of which will be presented 30 ly explained.

In operation:

35 Heat applied to the main generator 11 drives the cooling agent or refrigerant out of solution. I shall refer to ammonia as the cooling agent and water as the absorption liquid, but without limitation. The apparatus shown being of the equalized pressure type also contains an auxiliary agent for which fluid I prefer hydrogen. Ammonia 40 vapor driven out of solution in the generator passes through conduit 18 to rectifier 20, carrying along some entrained water or steam or both. The vapor of absorption liquid thus entrained is separated out from the 45 ammonia vapor in the rectifier and caused to return toward the generator through conduit 18. The cooling to effect the separation of absorption liquid is obtained due to the presence of liquid ammonia in the U-shaped member 21 which has been condensed in condenser tube 23. Ammonia vapor passes into conduit 23 from both member 22 outside the U-shaped member and from above the surface of liquid in that part of the U-shaped member 50 which is within jacket 22.

55 Liquid ammonia passes through conduit 26 and into evaporator 31 where it flows over the plates 50. Hydrogen is admitted to the evaporator through conduit 29. The ammonia diffuses into the hydrogen and evaporates thus taking up heat from the surroundings and producing refrigeration. A mixture of hydrogen and ammonia gas is formed which passes downwardly through conduit 60 32 and through space 38 and conduit 39 into

the lower part of absorber 40. In the absorber 40 weak absorption liquid separates ammonia from the hydrogen and the liberated hydrogen passes through conduit 27, space 35, tubes 37, space 36 and conduit 29 into the evaporator. Circulation of the hydrogen is produced between the evaporator and absorber due to the difference in specific weight of a mixture of ammonia gas and hydrogen on the one hand and hydrogen alone on the other hand.

70 Strong absorption liquid flows through conduit 42 and is lifted through thermosiphon tube 16 due to the heat applied to auxiliary generator 12 and the formation of vapor therein. The weak absorption liquid from which ammonia has been expelled passes through conduit 43 into the upper part of absorber 40 and flows over the plates 50 in the absorber. Circulation between the absorber and generator is produced by the lifting effect of auxiliary generator 12 and thermosiphon tube 16.

75 In apparatus of the general type above described it previously has been common to use 80 plates in the absorber and evaporator structure to maintain pools of liquid on the upper surfaces thereof. Raised rims around apertures in the plates have been used to maintain pools of liquid on these plates. Such 85 plates are shown in U. S. Patent No. 1,609,334 granted December 7, 1926. These plates are not designed to use the under-sides for gas and liquid contact. It has been proposed to use a fibrous material underneath plates of this nature for holding liquid but such fibrous material is not permanent, is not readily secured in place and does not afford the necessary conduction of heat. I provide a wire mesh screen 51 having a great number of 90 wires per square inch.

95 In the arrangement shown in Figs. 2 and 3 the plate 50 is made circular to fit the preferably circular form of the vessel in which it is contained with a segment cut-away to provide for flow of liquid downwardly from one plate to another. The underside of the plate carries the wire mesh 51 which is folded around the segment edge of the plate so as to be in contact with liquid on the upper surface. 100 While the side edge of one plate can serve to hold the wire mesh to the next adjacent higher plate, I prefer to secure the wire mesh to the plate by spot-welding or soldering the wire mesh in places to the plate. This further 105 provides good heat conductivity. The wire mesh holds a capillary film on the under-side of plate 50. Liquid is drawn by capillary attraction around the segment edge and to the under-side.

110 In the evaporator the liquid ammonia evaporates and conducts heat into the evaporator from the surroundings. In the absorber heat is expelled from the absorber into the sur-

- rounding cooling water coil. It will be obvious that the metal wire mesh provides good conductivity while at the same time holding the capillary film adjacent the metal plate so as to utilize the conductivity of the plate. This arrangement is particularly useful in the absorber for the reason that when only the upper side of the plate is used, the pool of liquid assumes different concentrations. 5 As ammonia is absorbed in the water the water can take up less ammonia. If a layer of concentrated absorption liquid lies on the top of a pool on an absorber plate it may prevent the absorption of ammonia by liquid lower down in this pool. By using the under-side of the plate in the manner I have suggested, this disadvantage is obviated in that the full 10 capability of absorbing of the liquid can be utilized. 15 Other forms of film-holding material may be used and it is even possible to cut grooves in the under-side of the plate in such a manner that a capillary film is continuously held on the under-side of the plate. 20 In Figs. 4 and 5 is shown a modified form of absorber plate wherein the wire mesh projects upwardly within apertures 53 and adjacent the raised rims 54. The wire mesh is held in place by a ring 55 and a cross-member 56. As the liquid on the upper-side of the plate flows over the rims 54 it will be readily seen that the liquid flows into the wire mesh 51. 25 Figs. 6 and 7 show a still further form wherein the wire mesh 51 is definitely spaced from the under-side of the absorber by means of a spacing member 57. A hole 58 is provided in the wire mesh diametrically opposite a hole 59 through which the liquid flows from one plate to the next lower so that the 30 liquid caught in the wire mesh is carried across the wire mesh to a greater or lesser extent and falls to the next lower plate at a point opposite the place where the wire mesh receives the liquid. This assures a greater 35 utilization of the wire mesh. 40 In Fig. 8 the arrangement is substantially as in Fig. 7 except that a piece of the wire mesh 60 is cut off and bent downwardly to give a natural path of flow of liquid from a given wire mesh to the next lower plate. This 45 form has a spacing ring 57 and a second ring 61 for holding the wire mesh in position and separating the plates. The wire mesh is preferably spot-welded between the two rings 57 and 61. Space ring 57 is relatively thin, for example one-thirtieth of an inch. 50 While I have described various modifications of my invention, it will be understood that I am not limited to the form above described but that other forms may be used within the spirit and scope thereof. It will be understood that my invention may be applied to absorber plates without being applied to 55 evaporator plates and to evaporator plates without being applied to absorber plates. 60

Having thus described my invention, what I claim is:

1. In a refrigerating system comprising interconnected vessels including a generator, a condenser, an evaporator and an absorber, said evaporator and absorber being interconnected to form a cycle for circulation of an auxiliary agent in the presence of which a cooling agent evaporates and plates within the said cycle of the system for providing gas and liquid contact surface, the combination therewith of wire screening under said plates and adjacent thereto for holding capillary films of liquid on the under-sides of the plates. 75
2. In a refrigerating system comprising interconnected vessels including a generator, a condenser, an evaporator and an absorber, said evaporator and absorber being interconnected to form a cycle for circulation of an auxiliary agent in the presence of which a cooling agent evaporates and plates within the said cycle of the system for providing gas and liquid contact surface, the combination therewith of perforated metal members under said plates and adjacent thereto for holding capillary films of liquid on the under-sides of the plates. 80
3. In a refrigerating system comprising interconnected vessels including a generator, a condenser, an evaporator and an absorber, said evaporator and absorber being interconnected to form a cycle for circulation of an auxiliary agent in the presence of which a cooling agent evaporates and plates within the said cycle of the system for providing gas and liquid contact surface, the combination therewith of metallic means for holding liquid on the under-sides of said plates. 85
4. In a refrigerating system comprising interconnected vessels including a generator, a condenser, an evaporator and an absorber, said evaporator and absorber being interconnected to form a cycle for circulation of an auxiliary agent in the presence of which a cooling agent evaporates and plates within the said cycle of the system for providing gas and liquid contact surface, the combination therewith of wire screening under said plates and attached thereto for holding capillary films of liquid on the under-sides of the plates. 90
5. In a refrigerating system comprising interconnected vessels including a generator, a condenser, an evaporator and an absorber, said evaporator and absorber being interconnected to form a cycle for circulation of an auxiliary agent in the presence of which a cooling agent evaporates and plates within the said cycle of the system for providing gas and liquid contact surface, the combination therewith of wire screening under said plates and adjacent thereto for holding capillary films of liquid on the under-sides of the plates. 95
6. In a refrigerating system comprising interconnected vessels including a generator, a condenser, an evaporator and an absorber, said evaporator and absorber being interconnected to form a cycle for circulation of an auxiliary agent in the presence of which a cooling agent evaporates and plates within the said cycle of the system for providing gas and liquid contact surface, the combination therewith of wire screening under said plates and adjacent thereto for holding capillary films of liquid on the under-sides of the plates. 100
7. In a refrigerating system comprising interconnected vessels including a generator, a condenser, an evaporator and an absorber, said evaporator and absorber being interconnected to form a cycle for circulation of an auxiliary agent in the presence of which a cooling agent evaporates and plates within the said cycle of the system for providing gas and liquid contact surface, the combination therewith of wire screening under said plates and attached thereto for holding capillary films of liquid on the under-sides of the plates. 105
8. In a refrigerating system comprising interconnected vessels including a generator, a condenser, an evaporator and an absorber, said evaporator and absorber being interconnected to form a cycle for circulation of an auxiliary agent in the presence of which a cooling agent evaporates and plates within the said cycle of the system for providing gas and liquid contact surface, the combination therewith of wire screening under said plates and adjacent thereto for holding capillary films of liquid on the under-sides of the plates. 110
9. In a refrigerating system comprising interconnected vessels including a generator, a condenser, an evaporator and an absorber, said evaporator and absorber being interconnected to form a cycle for circulation of an auxiliary agent in the presence of which a cooling agent evaporates and plates within the said cycle of the system for providing gas and liquid contact surface, the combination therewith of wire screening under said plates and attached thereto for holding capillary films of liquid on the under-sides of the plates. 115
10. In a refrigerating system comprising interconnected vessels including a generator, a condenser, an evaporator and an absorber, said evaporator and absorber being interconnected to form a cycle for circulation of an auxiliary agent in the presence of which a cooling agent evaporates and plates within the said cycle of the system for providing gas and liquid contact surface, the combination therewith of wire screening under said plates and adjacent thereto for holding capillary films of liquid on the under-sides of the plates. 120
11. In a refrigerating system comprising interconnected vessels including a generator, a condenser, an evaporator and an absorber, said evaporator and absorber being interconnected to form a cycle for circulation of an auxiliary agent in the presence of which a cooling agent evaporates and plates within the said cycle of the system for providing gas and liquid contact surface, the combination therewith of wire screening under said plates and attached thereto for holding capillary films of liquid on the upper sides of said plates. 125
12. In a refrigerating system comprising in- 130

- terconnected vessels including a generator, a condenser, an evaporator and an absorber, said evaporator and absorber being interconnected to form a cycle for circulation of an auxiliary agent in the presence of which a cooling agent evaporates and plates within the said cycle of the system for providing gas and liquid contact surface, the combination therewith of metallic means for holding liquid on the under-sides of said plates, said metallic means being arranged to contact liquid on the upper sides of said plates. 70
- 10 7. A vessel suitable for use in a refrigeration system comprising a plurality of superposed plates having parts adapted to permit formation of pools of liquid on said plates and wire screening under said plates and adjacent thereto for holding capillary films of liquid on the under-sides of the plates. 80
- 15 8. A vessel suitable for use in a refrigeration system comprising a plurality of superposed plates having parts adapted to permit formation of pools of liquid on said plates and perforated metal members under said plates and adjacent thereto for holding capillary films of liquid on the under-sides of the plates. 85
- 20 9. A vessel suitable for use in a refrigeration system comprising a plurality of superposed plates having parts adapted to permit formation of pools of liquid on said plates and metallic means for holding liquid on the under-sides of said plates. 90
- 25 10. A vessel suitable for use in a refrigeration system comprising a plurality of superposed plates having parts adapted to permit formation of pools of liquid on said plates and wire screening under said plates and attached thereto for holding capillary films of liquid on the under-sides of the plates. 100
- 30 11. A vessel suitable for use in a refrigeration system comprising a plurality of superposed plates having parts adapted to permit formation of pools of liquid on said plates and wire screening under said plates and adjacent thereto for holding capillary films of liquid on the under-sides of the plates, said wire screening being arranged to contact liquid on the upper sides of said plates. 105
- 35 12. A vessel suitable for use in a refrigeration system comprising a plurality of superposed plates having parts adapted to permit formation of pools of liquid on said plates and metallic means for holding liquid on the under-sides of said plates, said metallic means being arranged to contact liquid on the upper sides of said plates. 110
- 40 13. A plate for use in refrigerating apparatus comprising wire mesh on one side for retaining a capillary film of liquid against the plate. 115
- 45 14. In a refrigerating system comprising interconnected vessels including a generator, a condenser, an evaporator and an absorber, said evaporator and absorber being interconnected to form a cycle for circulation of an auxiliary agent in the presence of which a cooling agent evaporates, said plates having apertures and raised rims surrounding said apertures, the combination therewith of wire screening under said plates and adjacent thereto for holding capillary films of liquid on the under-sides of the plates, said wire screening extending upwardly within the apertures adjacent the raised rims. 120
- 50 15. In a refrigerating system comprising interconnected vessels including a generator, a condenser, an evaporator, and an absorber, said evaporator and absorber being interconnected to form a cycle for circulation of an auxiliary agent in the presence of which a cooling agent evaporates and plates within said evaporator for providing gas and liquid contact surface, the combination therewith of wire screening under said plates and adjacent thereto for holding capillary films of liquid on the under-sides of the plates. 125
- 55 16. In a refrigerating system comprising interconnected vessels including a generator, a condenser, an evaporator and an absorber, said evaporator and absorber being interconnected to form a cycle for circulation of an auxiliary agent in the presence of which a cooling agent evaporates and plates within said evaporator for providing gas and liquid contact surface, the combination therewith of metallic means for holding liquid on the under-sides of said plates. 130
- 60 17. In a refrigerating system comprising interconnected vessels including a generator, a condenser, an evaporator and an absorber, said evaporator and absorber being interconnected to form a cycle for circulation of an auxiliary agent in the presence of which a cooling agent evaporates and plates within said absorber for providing gas and liquid contact surface, the combination therewith of wire screening under said plates and adjacent thereto for holding capillary films of liquid on the under-sides of the plates. 135
- 65 18. In a refrigerating system comprising interconnected vessels including a generator, a condenser, an evaporator and an absorber, said evaporator and absorber being interconnected to form a cycle for circulation of an auxiliary agent in the presence of which a cooling agent evaporates and plates within said absorber for providing gas and liquid contact surface, the combination therewith of metallic means for holding liquid on the under-sides of said plates. 140
- 70 19. In a refrigerating system comprising interconnected vessels including a generator, a condenser, an evaporator and an absorber, said evaporator and absorber being interconnected to form a cycle for circulation of an auxiliary agent in the presence of which a cooling agent evaporates, said cycle includ- 145

ing means for providing gas and liquid contact and heat conductivity comprising a metal member having a drainage surface and wire screening adjacent said drainage surface for holding a capillary film of liquid against said member.

20. Plating for use in refrigeration apparatus having a drainage surface and wire mesh attached to said plating adjacent said drainage surface for retaining a capillary film of liquid against said plating.

21. In a refrigerating system comprising interconnected vessels including a generator, a condenser, an evaporator and an absorber, said evaporator and absorber being interconnected to form a cycle for circulation of an auxiliary agent in the presence of which a cooling agent evaporates, said cycle including means for providing gas and liquid contact and heat conductivity comprising a metal member having a drainage surface and a metallic perforated element adjacent said drainage surface for holding a capillary film of liquid against said member.

25. 22. In a refrigerating system comprising interconnected vessels including a generator, a condenser, an evaporator and an absorber, said evaporator and absorber being interconnected to form a cycle for circulation of an auxiliary agent in the presence of which a cooling agent evaporates, said cycle including means for providing gas and liquid contact and heat conductivity comprising a metal member having a drainage surface and wire screening adjacent to said drainage surface and spot-welded to said member for holding a capillary film of liquid against said member.

30 In testimony whereof I have affixed my
40 signature.

BO KARL GEORGE EHNBOM.
